GLOW LAMP STABILIZING SYSTEM

William West Moe, Stratford, Conn., assignor to Time, Incorporated, New York, N. Y., a corporation of New York

Application June 1, 1954, Serial No. 433,435

14 Claims. (Cl. 315—169)

The present invention relates generally to electrical systems in which electric signal variations are converted into light variations by glow lamps, and more particularly to improvements in such systems whereby a stabilized amplitude ratio is maintained between the electric signal variations and the light variations.

In facsimile systems, such as the color facsimile system disclosed in the applicant's copending application, Serial No. 251,898 (filed October 18, 1951) electric signals, having amplitude variations representing visual image information are applied to a glow tube used as a lamp whose light is directed upon a photosensitive medium. The intensity of the light emitted from the glow lamp varies in accordance with the amplitude of the applied signals with the result that there is exposed upon the medium the visual image information carried by the signals. It will be evident that for faithful reproduction of the visual image information on the medium, it is desirable and necessary to maintain a stabilized ratio between the amplitude of the signals applied to the glow lamp and the intensity of the light emitted therefrom.

As long as the average level of the amplitude of the applied signals remains substantially steady, it has been found that the mentioned ratio remains at a stabilized value within the tolerances required. When, however, there occurs a pronounced change in average signal level, it has been found that following this change the glow lamp undergoes what may be termed a time drift in the intensity of emitted light. If, for example, the average amplitude of the applied signal undergoes a sudden increase, the intensity of the emitted light undergoes a similar sudden increase, but thereafter, undergoes an additional "creeping" increase over a time interval. Similarly, if the average amplitude of the applied signal undergoes a sudden decrease, the intensity of the emitted light undergoes a similar sudden decrease, but thereafter, undergoes an additional "creeping" decrease over a time interval. Thus, in both situations a change in average level of the applied signal is followed by a transition period during which a variance occurs in the ratio between the amplitude of the signals applied to the glow lamp and the intensity of the light responsively emitted therefrom.

While it will be understood that the accuracy of applicant's explanation of why the observed glow lamp drift occurs in no way affects the merits of the present invention, it is believed that the described drift is caused by a sensitivity of the glow lamp to thermal conditions. When the current through the glow lamp is increased, this increased current causes a heating of the glow lamp, which in turn increases the light emitting capability thereof relative to the amount of current passing therethrough. Conversely, when there is a decrease in the current passing through the glow lamp, the glow lamp is cooled to decrease the light emitting capability thereof relative to the amount of current passing therethrough. The hypothesis of a thermal origin for the light intensity drift explains the fact that, whether the current increases or decreases, if thereafter the current remains constant, the

ratio between this current and the light emitted ultimately reaches a steady state value, the reason being that ultimately the glow lamp reaches a new state of thermal equilibrium with its environment. The hypothesis of thermal origin also explains the fact that the mentioned light intensity drift becomes significant only when there is a change in average level of the applied signal. High frequency variations in the signal around the same average level do not result in drift for the reason that such high frequency variations cause no more than a negligible change in the thermal condition of the glow lamp.

The mentioned variance in the ratio between the current exciting a glow lamp and the light emitted therefrom is highly undesirable in facsimile reproduction for the reason that the ratio variance may cause a clearly noticeable spurious streaking of the reproduced visual subject exposed upon the photosensitive medium. Not only is the streaking in itself undesirable, but in addition, in order to keep the streaking within the minimum bounds of acceptability for the reproduced visual image, it has been necessary in the past to operate glow lamps at considerably lower current values than those at which they would satisfactorily operate if the drift effect were not present (it being found with decreased current values that the drift effect diminishes by a factor which is greater than the decrease in current). Accordingly, as another disadvantage, the mentioned ratio variance precludes the use of the full capabilities of glow lamps.

It is an object of the invention, accordingly, to provide new and improved systems in which electric signals are converted into light by a glow lamp in a manner free of the above-noted deficiencies.

Another object of the invention is to provide systems of the above character wherein a stabilized ratio is maintained between the amplitude of the signals supplied as an input to the glow lamp and the intensity of the light responsively emitted by the glow lamp.

A further object of the invention is to provide systems of the above character wherein the glow lamp may be excited over a greater light output range than that previously practical.

A still further object of the invention is to provide systems of the above character which are adaptable to different type conditions encountered in the described converting action of the glow lamp.

These and other objects of the invention are attained by providing, in association with an electric signal channel which supplies the visual image signals to the glow lamp, an electric circuit means which is responsive to these visual image signals to generate a correction signal which varies in accordance with the time drift in intensity of the light emitted by the glow lamp. In conjunction with this electric circuit means there is provided a feedback means responsive to the mentioned correction signal for varying the amplitude of the visual image signals in the channel by an amount which maintains stabilized the ratio between the amplitude of input signal to the glow lamp and the intensity of the light responsively emitted therefrom.

The invention may be better understood from the following detailed description of representative embodiments thereof, taken in conjunction with the accompanying drawings, in which:

65 Fig. 1 is a diagram partly in block and partly in schematic of the color facsimile system disclosed in the aforementioned co-pending application, together with the additional system which is the subject of the present invention;

70 Fig. 2 is a set of graphs of aid in explaining the significance of the present invention; and

Fig. 3 is a schematic diagram showing an embodi-

ment of the invention which may be used in place of the embodiment shown in Fig. 1.

It will be understood in the description to follow that similar elements are designated by similar numerals, prime and double prime suffixes being used for the purpose of distinguishing the elements.

Referring now to Fig. 1, which shows in simple form the color facsimile system disclosed in much greater detail in the applicant's aforementioned co-pending U. S. application, Serial No. 251,898, the numeral 10 designates a color analyzing scanner which, in a well-known manner, is adapted to scan a colored original visual subject (not shown), and to convert the color information presented by the visual subject into three electric visual image signals representing three primary component colors, yellow, magenta and cyan. These three visual image signals are respectively supplied via the leads 11, 11', 11", to three electric signal channels 12, 12', 12", hereafter referred to as the yellow, magenta and cyan signal channels. The three color signals in passing through their corresponding channels are modified in various respects (hereafter described in more detail). Ultimately the modified colored signals emerge from the channels on output leads 13, 13', 13", to respectively drive the yellow, magenta and cyan glow lamps 14, 14', 14" in the sense that the intensity of the light emitted by each glow lamp is a function of the amplitude of the corresponding color signal. The light emitted from the glow lamps 14, 14', 14" is directed in a well-known manner onto three corresponding photographic emulsions (not shown) to impress thereon the visual image information carried by the respective color signals. The color facsimile system of Fig. 1 is thus adapted to produce three color component reproductions of the original colored visual subject presented to scanner 10.

In Fig. 1, the yellow channel 12 is, with regard to the present invention, essentially similar to the magenta channel 12' and the cyan channel 12". Accordingly, unless otherwise noted, the following description of yellow channel 12 applies as properly to the other electric signal channels.

To enlarge upon the details of the system of Fig. 1, the "yellow" visual information from scanner 10 appears upon lead 11 in the form of amplitude variations of a direct current signal. This yellow visual image signal is supplied by lead 11 as an input to the front end section 20 (shown in block form in Fig. 1) of yellow channel 12. Section 20 (as well as modifying the signal in ways not of present interest) converts the visual information of the yellow signal into the form of modulations on a high frequency (150 kc.) carrier, all as described in the aforementioned co-pending application. This modulated high frequency carrier signal is fed from the output of section 20 via lead 21 to a successive channel section 22 shown in Fig. 1 within the dotted lines 23, 24, 25, 26.

Section 22 represents, as hereafter more fully described, a section of the yellow signal channel 12 which has a controllable signal transfer ratio. In section 22 the yellow signal in the modulated high frequency carrier form is applied as an input to a pentode 30 by means of a coupling capacitor 31 which impresses the signal upon the control grid 32 of the pentode. The plate 33 of pentode 30 is coupled through resistors 34, 35 to a source of positive voltage supply (not shown) and is also coupled through a capacitor 36 with a parallel resonant circuit 37 tuned to the carrier frequency and coupled in effect at this frequency between the plate 33 and ground to form a plate load. Pentode 30 is otherwise coupled to act as an amplifier tube. Accordingly, pentode 30 and parallel resonant circuit 37 together form a tuned amplifier stage, the output of which appears across resonant circuit 37. As is well known, the amplification factor of this pentode amplifier stage varies commen-

surately with the effective impedance at the carrier frequency of the plate load.

The output from the tuned amplifier stage is fed via a coupling capacitor 38 and lead 39 to a succeeding section 40 in the yellow signal channel.

Section 40 comprises, in the order of signal flow direction, an amplifier stage and a cathode follower stage (neither being shown in detail), both of which stages are conventional and perform their usual and well-known operations. From section 40 the yellow signal in modulated high frequency carrier form is advanced to a rectifier and voltage doubler section 41 which acts as a demodulator to convert the "yellow" visual image information back into the form of amplitude variations of a direct current signal upon the output lead 42 for section 41.

The direct current yellow signal upon lead 42 is applied to the control electrode 43 of an electron discharge device 44 (as, say, a pentode of the 6AC7 type) within a channel section 45 outlined by the dotted lines 46, 47, 48, 49. The cathode 50 of vacuum tube 44 is coupled to ground through a variable resistor 51 within another channel section 52 outlined by the dotted lines 48', 53, 54, 55. Thus, the visual image information of the signal upon lead 42 will appear within channel section 52 in the form of a voltage across the variable resistor 51. The plate 60 of vacuum tube 44 is in circuit with a positive voltage supply (not shown) through a serial coupling with the "yellow" glow lamp 14 which may be a neon crater lamp of the R1135 type manufactured by the Sylvania Electric Co. Since glow lamp 14 and the anode-cathode path of tube 44 are thus in serial coupling, it will be seen that variation of the signal on lead 43 not only produces, in a well-known manner, a commensurate variation of the anode-cathode current through tube 44, but also produces a corresponding variation in current through glow lamp 14. This current variation through glow lamp 14 causes a related change in the intensity of the light emitted by the glow lamp. Accordingly, the light output of the glow lamp varies as a function of the input signal to tube 44, or, equivalently, as a function of the voltage developed across resistor 51 within channel section 52.

It will be understood that various circuits disclosed in the aforementioned co-pending application, but not pertinent to an understanding of the present invention, have been omitted from the showing and description of Fig. 1.

The foregoing description pertains to the color facsimile system as disclosed in the aforementioned co-pending application. Coming now to a consideration of the present invention, with the heretofore described facsimile system, in the presence of a pronounced change in average level of the yellow signal, the glow lamp 14 undergoes, as described, a time drift in intensity of the light emitted therefrom. For a better understanding of the nature of this time drift in light intensity, reference is made to Fig. 2, wherein the horizontal coordinate in the several shown graphs represents elapsed time, and the vertical coordinate represents signal level.

Considering first graph A of this figure, the solid line 60 represents the amount of current passing through glow lamp 14, whereas the dotted line 61 represents the intensity of the light responsively emitted therefrom, the values of current amplitude and light intensity both being expressed in arbitrary units of measure scaled off according to the same numerical scale along the vertical coordinate of graph A. It will be appreciated that the current and light intensity representations are idealized for clearer explanation to show simple assumed levels for these quantities. In practice, the current and light intensity would be much more irregular and complex than the showings thereof in graph A. However, the same principles would still apply.

Considering the significance of graph A, at time t_0 both the glow lamp current I_0 and the glow lamp light intensity L_0 are assumed to be at zero value corresponding to

minimum brightness or "black" for the visual image information. Assume now that at time t_1 the visual image brightness becomes maximum or "white." Under this condition, the glow lamp current I increases suddenly to a value I_1 , while the light intensity L correspondingly increases to a value L_1 , the units of measure being selected so that I_1 equals L_1 in graph A. From time t_1 to a later time t'_1 , the glow lamp current I remains constant at its initial increased value I_1 . During this same transitional time interval, however, the light intensity L instead of remaining constant at its initially increased value L_1 , continues to drift upward with a gradual leveling off until it reaches the value L'_1 at t'_1 , the time at which the drift in light intensity can be considered to become negligible. Following time t'_1 , both the current I and the light intensity L remain at their values I_1 and L'_1 , so that the ratio L/I becomes stabilized at a value for the units of measure employed of 20 units (for L) divided by 16 units (for I), or 1.25.

Assume now at time t_2 that the glow lamp current I suddenly decreases from its value I_1 of 16 units to a new value I_2 of 4 units, there being a net decrease of 12 units. The light intensity L'_1 undergoes a responsive decrease of 12 units from its value L'_1 of 20 units to a new value L_2 of 8 units. From time t_2 to a later time t'_2 , the current I remains constant at its initially decreased value I_2 . During this same transitional time interval, however, the light intensity L drifts downward from its initially decreased value L_2 with gradual leveling off until at time t'_2 it reaches the value L'_2 , the value at which the drift can be considered to be negligible. Following time t'_2 , the current I and light intensity L stay constant at their values I_2 and L'_2 with the result that the ratio L/I is re-stabilized at the value of 5 units (for L) divided by 4 units (for I), or 1.25.

Note that where there is a current decrease, as at time t_2 , it takes a longer interval ($t'_2 - t_2$) for ratio stabilization to be attained than the interval ($t'_1 - t_1$) required where there is a current increase. This longer transitional time period for a current decrease can be explained according to the thermal origin theory of the light intensity drift by the fact that it takes a glow lamp a longer period to cool in response to decreased current than to heat in response to increased current.

From the foregoing it will be seen that with the facsimile system as heretofore described, after a lapse of time following a pronounced change in average level of the glow lamp current, the current I and the intensity L of the light responsively emitted will be quantitatively related according to a ratio having a stabilized value. It will also be seen, however, that during transitional time intervals following the level change, the ratio between output light and input current, instead of being stabilized, will undergo a considerable variance. Note that this ratio variance effect is particularly aggravated when, as at time t_2 , the glow lamp has been in operation for awhile, the ratio L/I at this time being 8 units (for L) over 4 units (for I), or 2.00 in contrast to its later assumed value of 1.25.

The ratio variance is, of course, caused by the light intensity drift which over these transitional time intervals changes curvilinearly, and with continuously decreasing absolute slope from its initial value to its limiting or leveled-off value. To a reasonable approximation it has been found that the light intensity transition curve can be expressed by the exponential function:

$$L_c = k_1 I_c (1 - e^{-p_1 t})$$

where the quantities L_c , k_1 , I_c , e , p_1 and t represent, respectively, the instantaneous value of the change in light intensity, a multiplying constant, the change in average current level which initiates the drift, the Napierian base 2.71828, an exponential constant, and elapsed time. It will be understood that the value I_c is given plus and minus arithmetic signs when it represents, respectively, an in-

crease and a decrease, and that the exponential constant p_1 has different values m_1 and n_1 for an increase and a decrease. If the constant k_1 is given a value 0.25, the expression set forth above is appropriate to the transitional changes in light intensity shown in graph A.

To eliminate the variance in the ratio L/I , there is developed according to the present invention a correction voltage which is shown by line 63 in graph B. This correction voltage bears an analog relation to the described light intensity drift in that the correction voltage simulates the light intensity transition curve. Thus, the correction voltage also changes curvilinearly with decreasing absolute slope over the time intervals following a pronounced change in average level of the visual image signal. More specifically, if, as shown in graph B, the amplitude of correction voltage is denoted by E and the change in amplitude during a transitional time interval by E_c , the instantaneous value of E_c between steady state values E_s of E preceding and following an average level change of the visual image signal, can be represented by the expression:

$$E_c = k_2 V_c (1 - e^{-p_2 t})$$

wherein e and t represent the same quantities as before, k_2 and p_2 represent constants and V_c represents the change in average level of the visual image signal when this average level change is expressed in voltage form. Note that the quantity V_c has plus and minus arithmetic signs when, respectively, the average signal level increases and decreases.

The correction voltage so developed is utilized, as shown by line 64 in graph C, to cause a magnitude change M_c of the visual image signals in a sense opposing the direction of change of the average signal level. When the visual image signals are so varied, the magnitude change induced in the signals by the correction voltage offsets the drift in glow lamp light intensity induced by the change in average signal level for the reason that the changed signal strength decreases (or increases) the emitted light by an amount approximately equal to the increased (or decreased) extraneous increment of light caused by the drift. Accordingly, by using the described correction voltage with proper values for the constants k_2 and p_2 and a proper quantitative relation between correction voltage values and resulting amplitude values of the visual signal, the transition curve of emitted light intensity L is substantially eliminated so that the ratio L/I remains stabilized within the usual tolerances required, following average level changes of the visual signals.

As stated, the foregoing graphical representations of light intensity and current amplitude have been idealized for greater convenience of explanation. One of the simplifying assumptions which has been made is that the described channel will have a standardized operating characteristic of light intensity vs. signal amplitude which is both of a linear nature and of the same L/I value for any point on the characteristic. In other words, if, in the situation illustrated by graph A where no correction voltage is applied, the light intensity L is plotted against the signal amplitude I as the latter is changed slowly enough to eliminate the time drift factor of the lamp, the operating characteristic thereby obtained will be a straight line which is formed of (L, I) points, and which passes through the origin of the plot such that the ratio L/I has the same value for all points on the line as, say, at the respective points where I equals 16 units and 4 units. Also, if in the situation represented by graph C where correction voltage is applied, the operating characteristic of light intensity vs. signal amplitude is obtained in like manner (but including the effect of the correction voltage), the result will be a characteristic which again takes the form of a straight line passing through the origin of the plot. The characteristic obtained when correction

voltage is applied is, of course, the characteristic of principal interest to the present invention.

While it may be advantageous for the last-named characteristic to be linear and to pass through the origin of the plot, the present invention is not concerned so much with these features as with the feature that (irrespective of its linearity or the values obtained for the L/I ratio from point to point thereon) the characteristic of light intensity vs. signal amplitude shall be one which remains relatively invariable or "standardized" despite occurrences of the described time drift in intensity of the lamp. To state it another way, it is the purpose of the present invention to assure that, whatever may be the profile of the intensity-amplitude characteristic as plotted from (L,I) point to (L,I) point, the characteristic shall, at all times, be defined by approximately the same set of (L,I) points even though a time drift of intensity occurs in the lamp. This is what is meant by the statement made above that "the transition curve of emitted light intensity L is substantially eliminated so that the ratio L/I remains stabilized." The ratio L/I is considered to be stabilized when, for any given (L,I) point on the intensity-amplitude characteristic, the value of the ratio of quantities L and I , which are represented by this point, is a value which remains substantially constant despite the occurrence of a drift in the intensity of the lamp.

The results obtained by the described generation and feeding back of the correction voltage are shown in graph D by the line 65 representing light intensity. Note that in graph D, while the transition curve for L is completely eliminated between times t_1 and t'_1 , a residual transition curve remains between the times t_2 and t'_2 . This residual transition curve may be attributed to the fact that in the correction voltage of graph B the same value for the exponential constant p_2 is used for both a correction voltage increase and decrease, whereas, as described, the light intensity drift curves are characterized by different values m_1 and n_1 for their exponential constant p_1 when the visual signal average level undergoes, respectively, an increase and a decrease.

To develop the correction voltage shown in graph B for varying the visual signal amplitude as shown in graph C, there is provided, in accordance with the invention, a voltage modifying circuit 70 (Fig. 1) for the yellow signal channel 12. In voltage modifying circuit 70, a high impedance resistor 71 and a capacitor 72 of large capacitance value are coupled together to form an integrating means or integrating circuit, it being understood that the integrating circuit acts as an exponential voltage generator, rather than performing exact integration in a mathematical sense. For proper action as an integrating circuit, resistor 71 may have a value of one megohm, while capacitor 72 may have a value of 16 microfarads.

The two mentioned electrical elements form a serial coupling which, by a ground connection at one end and by a lead 73 at the other, is coupled to receive the voltage developed in channel section 52 by being connected across cathode resistor 51 of pentode 44. It will be recalled that this cathode resistor voltage is a manifestation of the visual image signal and will accurately reflect changes in level thereof. Accordingly, a pronounced increase in the average signal level will cause capacitor 72 to charge with corresponding development of a rising exponential voltage across its terminals, while a sudden decrease in average signal level causes capacitor 72 to discharge with corresponding development of a decreasing exponential voltage across its terminals. Thus, the integrating circuit of resistor 71 and capacitor 72 produces across capacitor 72 the correction voltage E in the manner shown by graph B (Fig. 2).

The correction voltage appearing at the ungrounded terminal 80 (Fig. 1) of capacitor 72 is supplied via a feedback circuit including the attenuating thyrite resistors 81, 82 to another thyrite resistor 83 which acts to control

the signal transfer ratio of section 22 of yellow channel 12. It will be recalled that in channel section 22 the yellow visual image signal is in the form of modulations on a high frequency carrier. Thyrite resistor 83 at the carrier frequency is in effect coupled across the resonant circuit 37 by a connecting lead 84 at one end of the resistor, and by a radio frequency bypass capacitor 85 connected between the other end of the resistor and ground. Thyrite resistor 83, through lead 84, also is in a circuit path for current developed in voltage modifying circuit 70 responsive to the correction voltage generated across capacitor 72, the mentioned current flowing from junction 80 through thyrite resistors 81, 82, thyrite resistor 83 upwards through lead 74, downwards through resonant circuit 37 and returning to ground.

As is well known, a thyrite resistor passes current as an exponential function of the applied voltage. Accordingly, a thyrite resistor may be said to have a non-linear resistance which varies in an opposite sense to the variance in the current passing therethrough. Assuming that an increasing correction voltage appears across capacitor 72, this voltage causes a current which increases, roughly, in an exponential manner to flow through resistor 83 with the result that the resistance thereof is correspondingly decreased. The resistor 83 in terms of the modulated carrier color signal in channel section 22 forms (in conjunction with resonant circuit 37) a significant component of the plate load for amplifier pentode 30. As described heretofore, the amplification factor of a pentode amplifier stage varies in accordance with the impedance of the plate load. Accordingly, as the resistance of thyrite resistor 83 is decreased by the current induced by the correction voltage, the impedance at the carrier frequency of the plate load for pentode 30 is correspondingly decreased. It follows that the signal transfer ratio for the modulated carrier between the input and output of channel section 22 will be varied to decrease in amplitude the output signal relative to the input signal. Thus, it is seen that thyrite resistor 83 represents a means for controlling the signal transfer ratio of the section.

If the signal transfer ratio of channel section 22 is so decreased, it is evident that the strength of the visual image signal appearing in direct current form upon control grid 43 of pentode 44 will also be decreased. This decrease in signal strength at pentode 44 reduces the current through glow lamp 14 to accordingly counteract (as shown in graph C, Fig. 2) the tendency of the glow lamp to drift upward in emitted light intensity responsive to an increase in average level of the visual image signal.

In a manner analogous to that given by the description above, in the presence of a decreasing correction voltage appearing across capacitor 72, the effective resistance of thyrite resistor 83 is increased to increase the plate load impedance of pentode 30 in channel section 22 to in turn increase the signal transfer ratio of this section. Hence, the signal strength at pentode 44 will rise to increase the glow lamp current by an amount which counteracts the tendency of the glow lamp to have a falling drift in emitted light intensity after a sudden decrease in average level of the visual signal.

Thyrite resistors 81, 82, which have the same voltage-current characteristics as thyrite resistor 83, represent circuit elements for attenuating the amount of correction voltage applied across resistor 83. Since all three resistors are of similar characteristic, it will be seen that the voltage across resistor 83 is directly proportional to the correction voltage even though the last-named resistor is non-linear and is in a series of voltage dividing resistors. It is not, however, essential to the present invention that strict proportionality be maintained between the correction voltage and the fraction thereof appearing across resistor 83.

The proper values for the constants k_2 and p_2 in the above set forth expression for correction voltage, and

the proper quantitative relation between V_c (the voltage across cathode resistor 51) and M_c (the responsive change in magnitude of the visual image signal) may be established in a manner well known to the art. To vary this quantitative relation, however, there is provided an adjustable control means in the form of a variable resistor 90 connected between the junction of thyrite resistors 82, 83 and ground. Adjustment of variable resistor 90 changes in effect the value of the constant k_2 in the above set forth expression for the correction voltage.

Referring now to Fig. 3, there is shown an alternative embodiment of the invention associated with the yellow signal channel 12 (Fig. 1), the same numerals being used to designate the elements in Figs. 1 and 3 which are the same. This alternative embodiment takes the form of a voltage modifying circuit 100 which, as before, receives over lead 73 an input signal from the cathode 50 of pentode 44, but which feeds back over return lead 84 its output signal to the yellow signal channel by applying its output signal through suppressor grid 101 of pentode 44 in channel section 45. In circuit organization, the voltage modifying circuit 100 includes a capacitor 102, a first resistor 103 and a second resistor 104 serially coupled in the order named between lead 73 and ground. These elements may have values of 16 microfarads, 1 megohm, and 3 megohms, respectively. The modifying circuit also includes a rectifier 105 in the form of a diode connected between the junction of resistors 103, 104 and ground. The output lead 84 for the modifying circuit is connected to the junction of capacitor 102 and resistor 103 to convey the signal at this point to the suppressor grid 101 of pentode 44. Note that (in contrast to Fig. 1) in Fig. 3 the suppressor grid 101 is disconnected from the cathode 50 of the pentode.

With regard to operation of voltage modifying circuit 100, the cathode resistor 51 in section 52 of yellow signal channel 12 manifests the yellow visual image signal in the form of a voltage. Responsive to a sudden increase in the average level of this voltage, the suppressor grid 101, by virtue of its coupling through lead 84, capacitor 102 and lead 73 to cathode 50, will undergo a sudden corresponding increase in voltage for the reason that the potential between the terminals of capacitor 102 cannot change instantaneously. The transconductance of pentode 44 varies in the same sense as the voltage on its suppressor grid. Hence, initially following a sudden increase in average signal level, pentode 44 will have a high transconductance permitting relatively high current flow through its anode-cathode path, and correspondingly through the glow lamp 14.

Following the sudden change in average level, however, capacitor 102 begins to charge negatively by flow of current from the capacitor through resistor 103 and diode 105 to ground, the capacitor 102 and resistor 103 forming together an integrating circuit which generates across the capacitor a decreasing exponential voltage, shown by the line 66 for the interval $(t'_1 - t_1)$ in graph E (Fig. 2). This decreasing exponential or correction voltage is imparted by lead 84 to suppressor grid 101 to correspondingly decrease the transconductance of pentode 44. Thus, the current through glow lamp 14 correspondingly decreases to offset the tendency of the glow lamp to drift upward in emitted light intensity responsive to the average level increase (of the visual image signal fed to control grid 43 of pentode 44 by lead 42). As a result, there is effected, as shown by the line 67 (representing light intensity) in graph F (Fig. 2), an elimination of the transition curve which characterizes (as shown in graph A) the yellow signal channel in the absence of a voltage modifying circuit of the sort described.

In accordance with the foregoing description, it will be noted that, in the case of the Fig. 2 embodiment, it is the channel section 45 (containing the pentode 44) which has the controllable signal transfer ratio. The ratio between the strength of the input signals on control

electrode 43 and the strength of the output signals (in the form of anode-cathode current variations) from pentode 44 is controlled by the voltage on suppressor grid 101 which governs the transconductance of the pentode.

It will be recalled that the Fig. 1 embodiment of the present invention in the presence of a sudden decrease in average signal level results in a greatly diminished, but residually remaining light intensity drift, shown in the interval between times t_2 and t'_2 for graph D. As heretofore stated, this residual drift is explainable in terms of the mathematical expression set forth above for the transitional change in light intensity in that the exponential constant p_1 has different values m_1 and n_1 for, respectively, an increase and decrease in average signal level. On the other hand, in the mathematical expression (set forth above) for the correction voltage, developed by the Fig. 1 embodiment, the exponential constant p_2 has the same value, say, m_2 , for both an increase and a decrease in average signal level. While the residual drift shown in graph D is so small as to be an insignificant factor in many facsimile system operations, there are other operations when the residual drift should be eliminated. Such elimination is accomplished by the embodiment of Fig. 3.

Regarding the mode of counteracting residual drift, as stated, in the presence of an average signal level increase, the capacitor 102 in Fig. 3 charges negatively by a flow of current from the capacitor through resistor 103 and diode 105 to ground. In this situation, diode 105 acts as a short-circuiting element between resistor 103 and ground, with the result that the exponential constant p_2 for the correction voltage across capacitor 102 has a value m_3 which is determined solely by the capacity and resistance of, respectively, capacitor 102 and resistor 103, the resistance value of resistor 104 being entirely excluded from the determination. When, on the other hand, there occurs a decrease in average signal level, the capacitor 102 will commence to charge positively by flow of current from ground through resistor 104, 103 and to the capacitor. In this latter situation, the diode 105 acts as an open circuit. Thus, in this latter situation, the exponential constant p_2 for the correction voltage across capacitor 102 will have a value n_2 determined by the resistance of resistor 104, as well as by the resistance and capacity of, respectively, resistor 103 and capacitor 102, the value n_2 being greater than the value m_2 . Accordingly, the diode 105 represents a form of polarity discriminator means which imparts different instantaneous values to the slope of the transient correction voltage according to whether the average level of the visual image signal undergoes an increase or a decrease.

By the action of diode 105 and as shown by comparison of the intervals $(t'_2 - t_2)$ and $(t'_1 - t_1)$ in graph E (Fig. 2), a decreasing correction voltage takes a longer time to reach its limiting change in amplitude (at time t'_2) than does an increasing correction voltage to reach its limiting change in amplitude (at time t'_1). By properly proportioning the circuit values for resistors 103, 104 and capacitor 102, respective curves for increasing and decreasing correction voltages may be obtained, so that, as shown in graph F, the ratio L/I is substantially entirely stabilized for both an increase and also a decrease in the average level of the visual image signal.

With the ratio L/I completely stabilized, as described, the aforementioned undesired streaking of the reproduced visual image can be fully eliminated. Also, the glow lamps can be operated over a much wider current range than that hitherto practical.

While the foregoing description has been addressed primarily to ratio stabilizing circuits for one particular (the yellow) electric signal channel of a facsimile system, it will be understood that the same means may be employed to stabilize the glow lamp ratios of a plurality of color component channels. It will also be understood that the present invention is of application in black-and-white

fascimile systems, and, in fact, in any system where a highly stable ratio is desirable between the strength of a visual image signal applied to a glow lamp and the intensity of the light responsively emitted therefrom. Note also that the invention is of application whether the correction signal is applied to the visual image signal in the form of a modulated high frequency carrier (the Fig. 1 embodiment) or in the form of a varying direct current signal (the Fig. 3 embodiment).

The embodiments shown in the drawings and described herein are obviously susceptible of considerable modification in form and detail within the spirit of the invention. The embodiments, therefore, are to be regarded as illustrative only and not as limiting the scope of the following claims.

I claim:

1. A system for stabilizing the ratio between the amplitude of visual image signals applied through an electric signal channel to develop current in a gaseous discharge lamp and the intensity of light which is responsively emitted from said lamp, and which may transiently drift in intensity following a change in average level of said signals, said system comprising, electric circuit means responsive to change in average level of said visual image signals in said channel for generating a transient correction signal in the form of an electrical transient which is representative in instantaneous amplitude of the transient drift in intensity of said emitted light, and feedback means responsive to said correction signal for varying the amplitude of said visual image signals in said channel by an amount which maintains said ratio at a constant value following changes in average level of said visual image signals.

2. A system for stabilizing the ratio between the amplitude of visual image signals applied through an electric signal channel to develop current in a gaseous discharge lamp and the intensity of light which is responsively emitted from said lamp, and which may transiently drift in intensity following a change in average level of said signals, said system comprising, a first section of said channel adapted to manifest said visual image signals as a voltage, electric circuit means responsive to a change in average level of the visual image signal voltage in said first channel section for generating a transient correction voltage which is representative in instantaneous amplitude of the transient drift in intensity of said emitted light, a second section in said channel having a controllable signal transfer ratio for visual image signals passing therethrough, and feedback means responsive to said correction voltage for controlling the signal transfer ratio of said second channel section to maintain said ratio at a constant value following said change in level.

3. A system for stabilizing the ratio between the amplitude of visual image signals applied through an electric signal channel to develop current into a gaseous discharge lamp and the intensity of light which is responsively emitted from said lamp, and which may transiently drift in intensity following a change in average level of said signals, said system comprising, a first section of said channel adapted to manifest said visual image signals as a voltage, electric circuit means responsive to a change in average level of the visual image signal voltage in said first channel section for generating a curvilinearly changing transient correction voltage which in amplitude progresses with decreasing absolute slope towards a limiting change in amplitude commensurate with said change in level, and which is representative in instantaneous amplitude of the transient drift in intensity of said emitted light, a second section in said channel having a controllable signal transfer ratio for visual image signals passing therethrough, and feedback means responsive to said correction voltage for controlling the signal transfer ratio of said second channel section to maintain said ratio at a constant value following said change in level.

4. A system for stabilizing the ratio between the amplitude of visual image signals applied through an electric signal channel to develop current in a gaseous discharge lamp and the intensity of light which is responsively emitted from said lamp, and which may transiently drift in intensity following a change in average level of said signals, said system comprising, a first section of said channel adapted to manifest said visual image signals as a voltage, electric circuit mean responsive to a change in average level of the visual image signal voltage in said first channel section for generating a curvilinearly changing transient correction voltage which in amplitude progresses with decreasing absolute slope towards a limiting change in amplitude commensurate with said change in level, and which is representative in instantaneous amplitude of the transient drift in intensity of said emitted light, polarity discriminator means selectively responsive to average level changes of different sign for imparting different instantaneous slope values to said curvilinearly changing correction voltage, a second section of said channel having a controllable signal transfer ratio for visual image signals passing therethrough, and feedback means responsive to said correction voltage for controlling the signal transfer ratio of said second channel section to maintain said ratio at a constant value following said change in level.

5. A system for stabilizing the ratio between the amplitude of visual image signals applied through an electric signal channel to develop current in a gaseous discharge lamp and the intensity of light which is responsively emitted as an output from said lamp, and which may transiently drift in intensity following a change in average level of said signals, said system comprising, a first section of said channel adapted to manifest said visual image signals as a voltage, electric circuit means responsive to a change in average level of the visual image signal voltage in said first channel section for generating a curvilinearly changing transient correction voltage which in amplitude progresses with decreasing absolute slope towards a steady state amplitude commensurate with the signal level following said change, and which is representative in instantaneous amplitude of the transient drift in intensity of said emitted light, a second section of said channel having a controllable signal transfer ratio for visual image signals passing therethrough, and feedback means responsive to said correction voltage for controlling the signal transfer ratio of said second channel section to maintain said ratio at a constant value following said change in level.

6. A system for stabilizing the ratio between the amplitude of visual image signals applied through an electric signal channel to develop current in a gaseous discharge lamp and the intensity of the light responsively emitted from said lamp, said system comprising, a first section of said channel adapted to manifest said visual image signals as a voltage, electric circuit means responsive to a change V in average level of the visual image signal voltage in said first channel section for generating a transient correction voltage E in accordance with the expression:

$$E = kV(1 - e^{-pt})$$

wherein V is given an arithmetic sign appropriate for the polarity of said average level change and wherein the symbols k , p , t and e respectively represent a constant, the time elapsed since said average level change and the Napierian base, a second section in said channel having a controllable signal transfer ratio for visual image signals passing therethrough, and feedback means responsive to said correction voltage for correspondingly varying the signal transfer ratio of said second channel section.

7. A system as in claim 6 further characterized by adjustable control means coupled in circuit with said correction voltage generating means to modify the voltage

developed thereby in a mode corresponding to assignment of different specific values to said constant k .

8. A system as in claim 6 further characterized by polarity discriminator means coupled in circuit with said correction voltage generating means to modify the voltage developed thereby in a mode corresponding to assignment of different specific values to said constant p for different polarities of said average level change.

9. A system for stabilizing the ratio between visual image signals applied through an electric signal channel to develop current in a gaseous discharge lamp and the intensity of the light responsively emitted from said lamp, said system comprising, a first section of said channel having terminals and adapted to manifest said visual image signals as a voltage between said terminals of said section, a second section in said channel having an input and an output and having a controllable signal transfer ratio between said input and output for visual image voltage signals passing therethrough, and a voltage modifying circuit coupled at one end with said terminals and at the other end with said second channel section to control the signal transfer ratio thereof in response to the changes occurring in the average level of the voltage between said terminals to thereby modify the voltage of said signals at the output of said second channel section relative to the voltage of said signals at the input thereof, said response of said signal transfer ratio of said second channel section being a response which is in proportion to the amplitude of said changes in average level, and which is exponential with respect to time.

10. A system for stabilizing the ratio between visual image signals applied through an electric signal channel to develop current in a gaseous discharge lamp and the intensity of the light responsively emitted from said lamp, said system comprising, a first section of said channel having terminals and adapted to manifest said visual image signals as a voltage between said terminals of said section, a first resistor and a capacitor serially coupled between said terminals as an average level integrating circuit, a second section in said channel having a controllable signal transfer ratio for visual image signals passing therethrough, and a feedback circuit coupled at one end across said capacitor and at the other end with said second channel section to control the signal transfer ratio thereof by the voltage across said capacitor.

11. A system as in claim 10 further characterized by an adjustable amplitude control device for varying in accordance with its setting the relative amplitude of the voltage supplied by said feedback circuit to said second channel section.

12. A system for stabilizing the ratio between visual image signals applied through an electric signal channel to develop current in a gaseous discharge lamp and the intensity of the light responsively emitted from said lamp, said system comprising, a first section of said chan-

nel having terminals and adapted to manifest said visual image signals as a voltage between said terminals of said section, a first resistor and a capacitor serially coupled between said terminals as an average level integrating circuit, a second resistor non-linear in resistance with applied voltage connected in said channel as a portion of a second section thereof and adapted to receive said visual image signals across its terminals, and a feedback circuit coupled at one end across said capacitor and at the other end across the terminals of said second resistor to control the resistance thereof by the voltage across said capacitor.

13. A system for stabilizing the ratio between visual image signals applied through an electric signal channel to develop current in a gaseous discharge lamp and the intensity of the light responsively emitted from said lamp, said system comprising, a first section of said channel having terminals and adapted to manifest said visual image signals as a voltage between said terminals of said section, a first resistor and a capacitor serially coupled between said terminals as an average level integrating circuit, an electron current control device connected in said channel as a second section thereof and having at least two control electrodes of which one electrode receives said visual image signals to correspondingly vary the current through said device, and a feedback circuit coupled at one end across said capacitor and at the other end with said other control electrode to control the transconductance of said device by the voltage across said capacitor.

14. A system for stabilizing the ratio between visual image signals applied through an electric signal channel to develop current in a gaseous discharge lamp and the intensity of the light responsively emitted from said lamp, said system comprising, a first section of said channel having terminals and adapted to manifest said visual image signals as a voltage between said terminals of said section, a capacitor and two resistors serially coupled between said terminals as an average level integrating circuit, a rectifier in shunt with one of said resistors, a second section of said channel having a controllable signal transfer ratio for visual image signals passing therethrough, and a feedback circuit coupled at one end across said capacitor and at the other end with said second channel section to control the signal transfer ratio thereof by the voltage across said capacitor.
